UNITED STATES PATENT OFFICE.

HENRY BLUM, OF NEW YORK, N. Y.

VALVE.

1,105,177.

Specification of Letters Patent.

Patented July 28, 1914.

Application filed July 2, 1913. Serial No. 776,924.

To all whom it may concern:

Be it known that I, HENRY BLUM, a citizen of the United States, and a resident of the borough of Manhattan, in the city, county, and State of New York, have invented certain new and useful Improvements in Valves, of which the following is a specification.

The object of this invention is to provide certain improved features of valve construction, and, more particularly, to provide a simple multiple valve structure in which a plurality of valves may be actuated selectively in a convenient manner from a common operating member.

The invention comprises the parts, improvements and combinations hereinafter described with reference to the accompanying drawings and more particularly pointed out in the claims.

In the said drawings: Figure 1 is a front elevation of a valve structure embodying the invention; Fig. 2 is a front elevation of another embodiment; Fig. 3 is a sectional plan view illustrating the application of the principles of the invention to a four-valve structure; Fig. 4 is a side view of Fig. 3; Fig. 5 is a plan view of Fig. 1, the operating shaft being shown in section; Fig. 6 is a vertical sectional view illustrating the construction of Fig. 2 with the supplementary plate shown in Fig. 8; Fig. 7 is a plan view of the shutter-like valve-actuating member, dotted lines being used to indicate its various positions with respect to the plunger valves; Fig. 8 is a detail view of a part shown in Fig. 6; Fig. 9 is a plan view of the follower plate shown in Figs. 1 and 5; and Fig. 10 is an elevation thereof.

The device includes a valve body, such as indicated at 10 in Fig. 1 or 10^a in Figs. 2 and 6, the same being provided with a plurality of valve chambers 11, in this instance two in number. Parallel bodily-movable valves, in the nature of plunger valves 12, operate within the body and have valve heads 13 which coöperate with suitable seats 14. The fluid may enter at the bottoms of the chambers and escape through the lateral passages 15 when the valves are open, or vice versa. At their upper or outer ends the stems of the valves are provided with suitable buttons 16, constituting valve projections to be engaged by the actuating mechanism. These buttons operate in en-

larged bores 17 formed in the body and are acted upon by expansion springs 18, which are confined within these bores and tend to close the valves.

A common rotary operating member, in the form of a shaft 19 having a handle 20, is mounted in the valve body in axial parallelism with the valves, and is provided with means whereby its rotation produces longitudinal movement of a selective actuating member 21.

In the construction shown in Figs. 1, 5, 9 and 10, the rotary movement of the handle is converted into endwise movement of the actuating member through the engagement of a cross-pin 22 in the shaft with a double cam 23 on a follower plate 24, the cam-engaging parts being made double to balance the thrust. An obvious reversal would be to mount the cam on the shaft and coöperating contact points or surfaces on the follower. In the particular construction shown, stops 25 are formed at the ends of the cam inclines, so as to limit the shaft to a partial revolution. At one extreme of the limit of handle movement the projecting portions of the pin 22 rest on the low portions of the cam, so that the follower is in its highest position with the valves closed, while at the other extreme of movement the pin bears against the high portions of the cam, with the result that the follower is in its lowermost position with the valves unseated. In this construction the shaft is rotatable in a bearing in the valve body intermediate the valves, and is held against endwise movement in an upward direction by a head 26 on its lower end within a recess in the body. The selective valve-actuating member 21 is disposed intermediate the follower 24 and the valve projections 16, so that downward movement of the follower, produced by the rotation of the operating shaft, forces the actuating member against one or other of the valves to unseat the same.

As shown more particularly in Fig. 7, the preferred form of selective actuating means comprises a shutter-like plate provided with an aperture, whereby it is mounted to swing on the operating shaft beneath the follower, and with two wings 28 which are so formed and proportioned as to enable the actuating member to overlie either or both of the valves, as indicated in this view. mediate the wings it is provided with a suitable handle 29, whereby it may be conveniently shifted. While this shutter-like plate constitutes the preferred form of 5 selective valve-actuating means, it will be understood that the advantages of the invention may be realized with various other forms of transversely-shiftable devices.

The follower plate 24 is preferably extended over the valve projections, opposite which it is provided with openings 30 of sufficient size to allow these projections to pass through without being actuated when the follower is depressed, provided that one 10 or both of these openings is not closed by the shutter-like actuating member. Means are provided for holding the follower against turning, a suitable embodiment of which is illustrated in the form of a pin 31 depending 15 from the follower in position to contact with a side face of the valve body. When the handle is turned to close the valves, the follower 24 and actuating member 21 are restored by an expansion spring 32, which is 20 interposed between the actuating member and valve body. The actuating member 21 is thus held between this spring and the follower, and in this manner is kept from turning with the shaft when the latter is rotated. 25 It will be observed that the inclines of the cam member 23 are of such gradual character as to render the valve mechanism self-holding at any degree of opening.

The construction shown in Figs. 2 and 6 is substantially similar to that just described, but differs therefrom in the manner of mounting the operating shaft 19^a in the body 10^a and the means whereby turning of the handle produces longitudinal 35 movement of the actuating member. In accordance with this construction, the lower or inner portion of the shaft is screw-threaded, as shown at 33, and engages with a threaded opening in the body instead of being merely rotatable in a bearing as in the other form. Thus, the operating shaft has endwise as well as rotary movement, and the endwise movement is imparted to the follower 24 and the actuating member 21 40 through a collar 34 on the shaft overlying the follower. The follower and the shutter-like actuating member both engage an unthreaded portion of the shaft and are held in position by the spring 32, which restores 45 these parts when the handle is turned in the valve-seating direction. It will be understood that the follower 24 is held against turning in the same manner as in the other construction.

50 Figs. 6 and 8 illustrate a further feature of the invention which comprises a supplementary plate or transversely-shiftable member 40, which is also rotatably mounted about the operating shaft and movable independently of the member 21, so that it

may coöperate with either wing thereof. This provides means whereby when the member 21 is set to open both valves, one valve may be opened to a greater degree than the other. By shifting the supplementary member to midposition it affects neither of the valves. The forms of the invention which have been described are two-valve structures, but it will be understood that the principles of the invention are not limited to any specific number of valves. Figs. 3 and 4 illustrate a four-valve construction, and in addition show certain further features of the invention which may be employed with advantage in certain instances. 70 The valve body 10^b comprises four valve chambers, in which are four plunger valves, the projecting plungers of which are designated 16 as in the preceding views. The valves are preferably arranged symmetrically, 90° apart, about a common operating shaft 19^b. This shaft may be the same as the shaft 19 of Fig. 1 or the shaft 19^a of Fig. 2, or of other suitable character, but as illustrated it resembles the construction of 80 Figs. 2 and 6. The transversely-shiftable, selective valve-actuating means is here shown as a single, elongated member 21^b pivoted at one end on the operating shaft and extended at the other end to form an operating handle 29^b, and being of such width as to be capable of being positioned in inoperative, intermediate relation to the valves. When in this position the operating shaft 85 may be screwed down until the valve projections are received within recesses 30^b in the follower 24^b, these recesses being closed at the top by caps or hollow bosses 41 so as to protect the valves from tampering. Means are provided for locking the parts 100 in this relation. Such means may be widely varied, but for purposes of illustration I have shown a padlock 42 the shackle of which passes through an opening in a pin 43, which in turn is passed through registering 105 openings in lugs 44, 45 on the follower and valve body respectively. The shank may also pass through an opening in the actuating member 21^b, though obviously this is not essential. In this construction, when the 110 mechanism is unlocked and the follower and actuating member raised, the latter may be swung into operative position over any one of the valve members, so as to unseat the same upon depression of the follower. 115

Fig. 4 shows the follower 24^b locked down directly against the top of the valve body, the member 21^b under this condition being received within a recess 46 in the valve body. 120

What I claim as new is:

1. In a valve structure, the combination of a plurality of bodily-movable valves, a valve-actuating member, and a rotary operating member separate from and having 13

means for moving said valve-actuating member toward and from the valves, said valve-actuating member being also mounted for guided movement relatively to said operating member and the valves so as to actuate said valves selectively.

2. The combination of a valve body, a plurality of parallel plunger valves therein, a valve-actuating member movable toward and from the valves in a direction parallel to their axes, and a rotary member for operating said valve-actuating member, the said valve-actuating member being mounted so as to be shifted transversely of the axes of said valves independently of said rotary operating member and being of such extent as to be capable of displacing one or more of the plunger valves at will.

3. A valve structure comprising a valve body having a plurality of valve chambers and seats, plunger valves coöperating therewith, and a rotary operating shaft mounted in said body and provided with a handle, in combination with a valve-actuating member adapted to be moved longitudinally by said shaft and being pivoted so as to be capable of swinging into positions where it operates one or other of the valves at will.

4. In a valve structure, the combination of a plurality of parallel bodily-movable valves, a valve-actuating member, and a rotary operating member axially parallel with said valves and having means for moving the actuating member longitudinally to unseat the same, said actuating member being angularly shiftable about the axis of the operating member for selective actuation of the valve.

5. In a valve structure, the combination of a plurality of plunger valves, an operating shaft, a follower actuated by the shaft, a selective valve-actuating member interposed between said follower and the valves and having an opening receiving the shaft about which it may be rotatably shifted, and a spring for restoring said follower and actuating member, said actuating member being interposed between the spring and follower.

50 6. In a valve structure, the combination of a plurality of plunger valves, a rotary operating shaft, a follower thereon moved axially thereby, and a selective valve-actuating member disposed shiftable between said

follower and the valves so as to actuate the 55 latter selectively.

7. In a valve structure, the combination of a plurality of plunger valves, a rotary operating member, a follower movable longitudinally thereby and held against turning, and a selective valve-actuating plate having an opening receiving said shaft, wings so proportioned that it may engage either or both of the valves and a handle for shifting it.

60 8. In a valve structure, the combination of a plurality of plunger valves, a rotary operating shaft, a follower adapted to be moved longitudinally thereby and having openings through which the projections of 70 the plunger valves may pass, and a shutter-like valve actuator mounted to swing about the axis of the shaft for selectively closing said openings.

65 9. In a valve structure, the combination of a plurality of bodily-movable valves, a rotary operating member, and two or more superposed plates between said operating member and valves, said plates being independently shiftable transversely of the direction of valve movement so as to effect variable and selective operation of the valves.

10. In a valve structure, the combination of a plurality of bodily-movable valves, a rotary operating member, a valve-selecting 85 member movable longitudinally by said operating member to actuate the valves and transversely shiftable independently of the operating member for valve selection, and a supplementary transversely-shiftable member for varying the degree of valve opening.

90 11. In a valve structure, the combination of a plurality of valves, a common rotary operating member, a follower, a cam whereby the operating member moves the follower 95 toward the valves, and a selective valve-actuating member movable by the follower toward the valves to actuate the same, said selective member being also shiftable independently of said follower in order to select the desired valve or valves.

In witness whereof I have signed my name in the presence of two subscribing witnesses.

HENRY BLUM.
